UNITED STATES PATENT OFFICE.

GEORGE ABREY, OF OSCEOLA, ARKANSAS.

CHOCK-BLOCK.

1,185,038.

Specification of Letters Patent.

Patented May 30, 1916.

Application filed December 22, 1914. Serial No. 878,576.

To all whom it may concern:

Be it known that I, GEORGE ABREY, a citizen of the United States, residing at Osceola, in the county of Mississippi and State 5 of Arkansas, have invented certain new and useful Improvements in Chock-Blocks, of which the following is a specification.

My invention relates to an adjustable log wagon chock block.

10 The primary object of my invention resides in the provision of a novel supporting means associated with the bolster of a wagon body for supporting logs and preventing longitudinal movement of the logs with respect to the wagon, the supporting means 15 having novel log limiting means mounted therein for preventing the transverse movement of the logs on the wagon.

Another object of my invention resides in 20 the provision of a novel log limiting means which in this instance includes a chock block slidably associated with the supporting means, both the supporting means and the block having novel means associated therewith for adjustably holding the limiting means in a set position on the supporting means.

A still further object of my invention resides in the novel identical means for mounting the adjusting and supporting means on 30 the wagon bolster.

A still further object of my invention resides in the provision of a novel means provided in the chock block for receiving the 35 chain used for adjusting purposes, the block being also provided with novel means communicating with the receiving means for facilitating the locking of the chain in the block.

40 A still further object of my invention resides in the construction of a novel chock block, the latter being also provided with improved means for facilitating the removal of the chain in the event of the same 45 becoming jammed therein and is also provided with novel means for facilitating the removal of the block from the supporting means or channel iron.

50 A still further object of my invention resides in the provision of a device of the character described that is simple in construction, efficient in operation and one that can be manufactured and placed on the market at a minimum cost.

55 Other objects as well as the nature, characteristic features and scope of my inven-

tion will be more readily understood from the following description taken in connection with the accompanying drawings and pointed out in the claims forming a part of 60 this specification.

In the drawings: Figure 1 is a side elevational view of my invention applied to the rear bolster of a wagon; Fig. 2 is an enlarged longitudinal and vertical sectional 65 view of the chock block; Fig. 3 is a front end elevational view of the chock block; and Fig. 4 is an enlarged rear end elevational view of my improved chock block showing to advantage the novel means for receiving 70 and locking the chain therein.

Referring more particularly to the drawings in which similar reference numerals designate like or corresponding parts throughout the different views, I connect 75 to the rear axle 1 of a vehicle, the usual wagon hounds 2, on which are disposed the rear bolster 3, the latter being positioned directly above the rear axle 1. Disposed on the bolster 3 and extending beyond the 80 ends of the axle is my improved channel iron 4 for receiving and supporting logs, the sides 5 of which prevent longitudinal movement of the logs with respect to the wagon. Disposed within the channel iron 85 4 beyond the sides 5 thereof is a metallic plate 6, the respective ends of which are slightly upturned for a purpose to be hereinafter described and which plates are provided with an opening through which is 90 passed a bolt 7, the latter also extending through the channel iron, bolster, hound and axle and serves the purpose of providing a rigid and removable connection between 95 these parts. Arranged in close relation with the inner surfaces of the sides 5 of the channel iron and resting upon the bottom thereof is my improved chock block which, in this instance consists of a substantially hollow rectangular body, the sides 8 of which 100 slope downwardly as at 10 from the front end 9 of the rear end 11 in order to conform substantially to the outer surface of the log. The front end 9 of the body is provided adjacent its upper end with a 105 circular aperture 12 through which is received the free end of a chain 13, the inner end of the chain being connected to one of the upturned ends of the plate 6.

In order to hold the block in various adjusted positions within the channel iron, I have positioned a longitudinal slot 14 in the

front end 9, the upper end of the slot being arranged in communication with the aperture 12 so that the link of the chain which is receivable within the aperture may be arranged and inserted within the slot for locking the chock block and limiting the outward movement of the same within the channel iron. A circular recess 15 is depressed about the slot 14 and constitutes a suitable bearing surface for the end of the adjacent link which is disposed in a plane at substantially right angles to the plane of the link within the slot 14 and facilitates the locking of the chain in the block. The upper edge 15 of the rear end 11 is provided substantially intermediate its edges with a recess 16 for receiving the chain and when the same is being extended through the aperture 13, it being obvious that the upper edges of the shortened rear end constitutes substantial guards for preventing the same from being broken due to the weight of a log thereon. Strengthening ribs 17 are also provided at the juncture of the lower inner surfaces of the sides 10 and end pieces 9 and 11.

In the event that the chain becomes jammed in the slot 14, I find it expedient to provide enlarged openings 18 in the sides 10, these openings permitting of the insertion of a suitable tool for lifting the chain from the slot especially when a log is disposed on the block which prevents access from the open upper end of the chock block.

In the event that the block becomes jammed within the sides 5 of the channel iron 4 and it is impossible to remove the same in the ordinary manner, I have provided a recess 19 in the lower edge of the front end 9, said recess permitting of the reception of a suitable tool for forcing the block upwardly from the channel iron.

When logs are being placed on the channel iron, I have found it expedient to remove the block from the iron and slide the same to the outer end on the chain 13 to a position adjacent the hook 20 secured thereon, the said hook being engageable in an ordinary locking chain, not shown, for facilitating the loading of the wagon with logs.

Although I have shown and described the preferred embodiment of my invention, I desire to be understood that I am not to be limited to the exact details shown, however, great stress is laid upon the arrangement of

the novel arrangement of the channel iron 55 having the improved block adjustably associated therewith for preventing the longitudinal and transverse movement of the logs with respect to the wagon.

From the above description taken in connection with the accompanying drawings, it can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention, what I claim as new and desire to secure by Letters Patent, is:—

1. The combination with a channel iron 80 disposed on a bolster, an attaching clip connected to the center of the channel iron, a block slidably supported within the channel iron, the front face of the block being provided with an opening and a slot, a chain 85 connected to the attaching clip and insertible in the opening and engageable with the slot for holding the block in a set position, the sides of said block being provided with openings for facilitating the disengaging of the 90 chain from the slot.

2. As an article of manufacture, a chock block including a rectangular body, the front wall of which is provided with a chain receiving recess, the rear wall of the body 95 being higher than the front wall and provided with an opening and a communicating slot adapted to receive and lock a chain, and the front surface of the rear wall being depressed about the slot to provide a recess 100 whereby to prevent accidental disengagement of the chain.

In testimony whereof I affix my signature in presence of two witnesses.

GEORGE ABREY.
